UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S WRAP.

SPECIFICATION forming part of Design No. 14,916, dated March 25, 1884.

Application filed February 13, 1884. Term of patent 3½ years.

To all whom it may concern:

Be it known that I, CATHERINE O'HARA, of the city, county, and State of New York, have invented and produced a new and original Design for a Pattern of a Lady's Wrap, (numbered 5 9,131;) and I do hereby declare that the engraved prints accompanying this specification convey to any one accustomed to use paper patterns a clear understanding of how a garment made up by the pattern will appear.

The design shows loose-fitting fronts, each falling in a deep point below the closing; a half-fitting back, falling in two deep points over a

deeper square-skirt portion; wide sleeves, each falling in a deep point, and gathered to stand 15 high at the shoulders, and a standing collar.

What I claim as my invention, and desire to secure by Letters Patent, is—

The design for a lady's wrap, as shown in the engraved prints accompanying this specification.

CATHERINE O'HARA.
